UNITED STATES PATENT OFFICE.

PETER McG. McBEAN, OF SAN FRANCISCO, CALIFORNIA.

ROOFING-TILE.

1,289,492.

Specification of Letters Patent. Patented Dec. 31, 1918.

Application filed January 8, 1917. Serial No. 141,144.

To all whom it may concern:

Be it known that I, PETER McG. McBEAN, a citizen of the United States, residing at the city and county of San Francisco and State of California, have invented new and useful Improvements in Roofing-Tiles, of which the following is a specification.

This invention relates to roofing tiles.

The object is to enable these tiles to be made economically in great quantities and under such conditions that all sagging or warping or tendency to get out of shape while the material is in plastic condition, is overcome.

15 Tile roofs are made up of concavo-convex tile sections which are usually laid with their axes of curvature in line from the eaves of the roof to the ridge and alternately with the concave and the convex surfaces uppermost; thus, a line of tile will be laid upon a roof, with the convex side downward, and the succeeding tiles in the line sufficiently overlapping the upper ends of the one below, to insure a continuous flow of water to the 25 eaves, or discharge. The next parallel tiles on each side will be laid with the convex sides uppermost and they are laid in such relation to the first-named tiles that the edges of the convexly surfaced tiles will rest in the concavities of those first laid, and at a sufficient distance apart to provide clear 30 channels for the escape of water which falls upon the roof or surface covered by the tiles, the convex surfaces discharging each side 35 from the top of the curve into the concave channels.

The tiles may be made of any lengths or sizes convenient for manufacturing, transportation and storage. In order to economize space in storage and transportation they should be made to nest.

Where these tiles are made singly it is difficult to produce them economically, or perfect in design or form. A single tile 45 made of plastic material like clay, is very liable to sag or warp, or otherwise become misshapen during the processes of manufacturing or baking, so that it will neither nest properly nor will it match up with its mates, 50 or look, act or fit right when laid on a roof.

The present invention comprehends the making of tiles in multiple at a single operation and in such manner and form that they will not only nest when separated and 55 stacked but the tiles of a unit will mutually support one another during the periods of

formation or baking; the unit after baking being separated into its tile components along weakened lines of juncture, the finished and separated tiles being all counterparts one of the other, and adapted to nest for storage and transportation, and proper laying on the roof.

In my Patent #1,184,254, issued May 23, 1916, I have shown an apparatus whereby such a tile can be produced, and I have again illustrated the apparatus here, although it is manifest that the shape and construction of the apparatus may be varied to make two or three, or more tiles at one 60 operation, or change the size or form of the finished tiles without altering the principle of the invention.

Having reference to the accompanying drawing:

Figure 1 is a sectional view of the fragments of the die and core suitable for practising the invention.

Fig. 2 is an end view showing the die, core and intermediate form where the tile unit 80 consists of three sections.

Fig. 3 is a perspective of a plastic material, or tile unit, after it has emerged from the die and been cut off to the desired length.

Fig. 4 is a detail showing the score knives 85 on the die and core.

Fig. 5 is a detail showing the score marks made on the plastic material as it emerges from the die.

Fig. 6 shows a tile unit of three sections. 90

Fig. 7 shows a tile unit of two sections.

Fig. 8 is a diagrammatic view of the die and a cutter.

Having reference to the accompanying drawing, A is the outer member, usually 95 made of metal of great strength so as to resist pressure, and B is the core. The space C between these parts represents the shape of the article to be produced.

D is an auger, screw, piston, plunger, or 100 other appropriate means for feeding, propelling or forcing the plastic material through the die or mold. E is a cutter of any suitable design or structure for severing the cylindrical body of plastic matter as it 105 issues from the die or mold into convenient tile lengths F.

The inner surface of the part A is made cylindrical. The core B, has its periphery formed of a plurality of segmental arcs of a 110 curvature eccentric to that of the cylinder A, so that the space to be filled, and the re-

sulting product will be a number of crescent shapes, as shown in Figs. 2, 3, 6 and 7. At the junction and thinnest part of each section scoring knives 2 are fixed in the die or mold, so that when the plastic material is forced through the die or mold these score knives will form grooves 3, along which the segments may be easily separated before or after baking. By retaining the structure 5 complete and undivided after its emergence from the die and while still in a green state, I am enabled to retain the shape and prevent it from warping or being misshapen before or during baking; the grooves or score marks 10 enabling the units to be easily separated before or after baking. Each unit as it is cut off is of uniform cross section at all points in its length, with the inner and outer surfaces of each tile section of the unit lying 15 in eccentric arcs of the same radii. The plastic article as a unit is preferably maintained as a unit during the entire process of manufacture including baking; the tile sections going to make up the unit being subsequently severed from their mates along the 20 weakened lines of juncture 3.

By reason of the crescent shape, the inner surfaces, having the same radius as the outer surface, but struck from different centers and each tile being a cylindrical segment as distinguished from one of conoidal form, the tiles will fit closely upon the exterior surface of the preceding tile when stacked up, and any number of the tiles may 25 thus be piled up and will nest perfectly through their length without danger of fracture, and less space will be occupied. Of course, if it is desired to make a tile unit simply in two sections, as shown in 30 Fig. 7, the die members are shaped accordingly. In Figs. 3 and 6, the tile sections of the unit are approximately 120° in length, measuring transversely of the tile, but obviously the length of the arc in each case depends on the desired amount of trough, or 35 ridge of the tile.

In all instances, preferably the outer or convex surface of the finished tile is a cylindrical arc, and the inner or concave surface 40 is a similar arc, having the same radius, but a different center. By placing this center at a distance from the first center, equal to the thickness required at the center of the tile, and completing the line of curvature, 45 the ends of the interior arc will approach those of the exterior one, thus making a transverse section of a tile in the form of a crescent. The two curvatures being equal, it is manifest that the finished tiles will nest 50 perfectly throughout their length when superimposed in piles.

The tile units are cylindrical in form, and uniform in cross section from end to end; the cutter E moving to cut the plastic cylinder into suitable tile lengths as it issues from 55

the die or mold; each tile section being a segment of a cylinder.

By this method of manufacture wherein a unit is produced containing a plurality of tiles, it is not only possible and practical for 70 the manufacturer to obtain economically a greater increased output over any method by which tiles are formed singly, but what is more important, in this unit, each section, which ultimately becomes a finished tile, 75 mutually supports the other section, and the tendency to sag and warp previously mentioned, is entirely obviated, so that a more uniform and better product is produced and cheaper than by making the tile singly. 80

In process of manufacture the unit may be stood on end, which is a further assurance against the plastic tile becoming misshapen.

By the term "cylinder" as used herein 85 with respect to a tile unit, I refer to any tubular structure irrespective of cross-sectional shape, in which there are a multiplicity of mutually supporting tile members or tile sections embodying the characteristics 90 above specified.

Having thus described my invention, what I claim and desire to secure by Letters Patent is—

1. The method of manufacturing roofing 95 tiles from plastic material, which consists in forcing the plastic material through a mold or die so as to produce simultaneously in cylindrical form a number of mutually supporting tiles which are joined along 100 laterally weakened lines of juncture, severing the molded plastic material into units of tile lengths, the tile sections of a unit having their inside and outside surfaces lying in arcs of the same radius, but the inside 105 and outside surfaces of each tile being described from different axes, and baking the tile sections.

2. The method of manufacturing tiles 110 from plastic material, which consists in the production of a cylindrical unit composed of mutually supporting connected tile sections separable along a weakened line of juncture, the unit being in uniform cross section from end to end, and the inside and outside surfaces of each tile section lying in eccentric 115 arcs of equal radii and baking the tile sections.

3. An article of manufacture, comprising 120 a unit containing a plurality of tile sections united together into a continuous body having transverse convexity and separable into a plurality of tiles, each tile being a segment of a cylinder, the tile sections being joined to one another along weakened lines and 125 each tile section mutually supporting the other during the process of manufacture, and the inside and outside surfaces lying in eccentric arcs of equal radii.

4. An article of manufacture, comprising 130

a plurality of conjoined tile sections united along weakened lines to permit their separation, each section mutually supporting the other during the process of manufacture, 5 and each section being a segment of a cylinder with the inside and outside surfaces lying in eccentric arcs of equal radii.

5. As an article of manufacture, a structure composed of a plurality of crescent 10 shaped tiles, the outer and inner peripheries of which are formed to fit and nest with each other.

6. A roofing tile in the form of a cylindrical segment having its exterior and interior surfaces of curvatures formed upon the 15 same radius, but from separated centers.

7. The method of manufacturing roofing tiles from plastic material which consists in

forcing the plastic material through a die or mold to produce a plastic tube, cutting 20 this plastic tube into appropriate tile lengths, each length of severed tube embodying a plurality of mutually supporting tile sections, each section having inside and outside surfaces of the same radial length, but 25 described from different axes, subsequently baking the severed lengths and later separating the tile sections.

In testimony whereof I have hereunto set my hand in the presence of two subscribing 30 witnesses.

DISCLAIMER.

1,289,492.—*Peter McG. McBean*, San Francisco, Calif. ROOFING-TILE. Patent dated December 31, 1918. Disclaimer filed March 9, 1921, by the assignee, *Gladding, McBean & Company*.

Hereby enters this disclaimer—

“To those parts of claims 5 and 6 of said patent and specifications in the following words, to wit:

“Your petitioner does hereby disclaim from claim 6 of said Letters Patent No. 1,289,492 any roofing tile or construction except where the said roofing-tile is a separated part of an original cylindrical structure, and which tile, after severance from said structure, possesses the further characteristics that its lateral edges are parallel for the entire length of the tile and the tile is of uniform cross-section from end to end; and disclaims from claim 5 of said patent any article except where the structure is composed of a plurality of connected crescent-shaped tiles separable along parallel weakened lines, the outer and inner peripheries of which tiles are formed of the same radial length but generated from different axes, so that the tiles, when separated, are adapted to fit and nest with each other.”
